UNITED STATES PATENT OFFICE.

LEWIS C. BAYLES, OF EASTON, PENNSYLVANIA, ASSIGNOR TO INGERSOILL-BAND COMPANY, OF NEW YORK, N. Y., A CORPORATION OF NEW JERSEY.

FLUID-PRESSURE-OPERATED HAND-TOOL.

1,091,112.

Specification of Letters Patent. Patented Mar. 24, 1914.

Application filed December 11, 1911. Serial No. 665,021.

To all whom it may concern:

Be it known that I, LEWIS C. BAYLES, a citizen of the United States, and resident of Easton, in the county of Northampton and 5 State of Pennsylvania, have invented a new and useful Improvement in Fluid-Pressure-Operated Hand-Tools, of which the following is a specification.

The object of my invention is to provide 10 a fluid pressure operated hand tool, such, for instance, as a riveting or chipping hammer in which the cylinder and its handle are bolted together thereby doing away with the screwed and clamped construction usually employed and obviating entirely all 15 danger of slipping between the handle and cylinder.

A further object is to provide a tool of the above character which will present a 20 very neat and attractive appearance, the bolts being arranged in alinement with the handle grip and housed within the handle and cylinder.

A still further object is to provide certain 25 improvements in the construction, form and arrangement of the several parts whereby the fastening bolts are locked against unintentional displacement between the cylinder and handle, the bolts being so secured that 30 they cannot be inserted or removed without the removal of the cylinder from the handle.

A practical embodiment of my invention is represented in the accompanying drawings, in which—

35 Figure 1 represents in side elevation a portion of a fluid pressure operated hand tool embodying my invention, Fig. 2 is a view of the same partly in longitudinal vertical central section and partly in side elevation, Fig. 3 is a section taken in the plane of the line A—A of Fig. 2, and Fig. 4 is a section taken in the plane of the line B—B of Fig. 2.

The handle of the tool is denoted by 1 and 45 the cylinder by 2. The inner end 3 of the cylinder is inserted into the central bore 4 in the face of the handle and the cylinder is provided with an external flange 5 opposite the face of the handle. The bolts for locking the handle and cylinder together are 50 arranged lengthwise of the tool and in alinement with the handle.

The handle is provided with oppositely arranged lateral recesses 6 in the walls of

the bore 4 for housing the heads 7 of the locking bolts. The handle is further provided with oppositely arranged longitudinal recesses 8 in the walls of the bore 4 leading from the lateral recesses 6 to the face of the handle for housing the inner portions of the shanks 9 of the locking bolts. The flange 5 of the cylinder is provided with oppositely arranged longitudinal holes 10 through which the shanks 9 of the bolts extend. Nuts 11 have a screw threaded engagement with the ends of the shanks 9 of the bolts beyond the flanges 5 for removably securing the cylinder to the handle. Lock washers 12 may be interposed between the nuts 11 and the flange 5 for preventing the unintentional unscrewing of the nuts. To more compactly house the parts, the nuts 11 and lock washers 12 may project into recesses 13 in the outer walls of the cylinder 2.

In assembling the parts, the bolts must first be inserted into their lateral and longitudinal recesses in the handle by way of the bore 4 before the inner end of the cylinder 2 is inserted into the bore. When the inner end of the cylinder is inserted into the bore 4 to bring its flange against the face of the handle, the screw threaded ends of the shanks of the bolts will be inserted through the holes 10 in the flange, the inner end of the cylinder serving to hold the bolts in their recesses in the handle against unintentional displacement.

It will be seen that the tool constructed as hereinabove set forth may have its handle and cylinder rapidly secured together or taken apart, the tool at the same time presenting a very neat and attractive appearance. It will furthermore be seen that there can be no turning movement of the cylinder with respect to the handle, the bolts serving to interlock the two parts together.

What I claim is:—

1. A hand tool of the character described comprising a cylinder, its handle having a grip extending transversely of the tool and separate bolts engaging the cylinder and handle upon opposite sides of the tool for rigidly securing them together, said bolts having their heads housed within the handle.

2. A hand tool of the character described comprising a cylinder, its handle and bolts for securing them together, said handle hav-

ing a central bore and lateral recesses in the walls of the bore for housing the heads of the bolts.

3. A hand tool of the character described comprising a cylinder, its handle and bolts for securing them together, said handle having a central bore and lateral recesses and longitudinal recesses in the walls of the bore for housing the heads and shanks of the bolts.

4. A hand tool of the character described comprising a cylinder, its handle and bolts for securing them together, said handle having a central bore and lateral recesses in the

walls of the bore for housing the heads of the bolts, and said cylinder having a flange through which the shanks of the bolts extend and nuts engaging the shanks beyond said flange.

In testimony, that I claim the foregoing as my invention I have signed my name in presence of two witnesses, this seventh day of December 1911.

LEWIS C. BAYLES.
